Specification for Design.

Patented May 15, 1917.

Application filed March 27, 1917. Serial No. 157,837. Term of patent 7 years.

To all whom it may concern:

Be it known that I, HARRY HUMPHREYS, a citizen of the United States, and a resident of Lancaster, in the county of Lancaster and State of Pennsylvania, have invented a new, original, and ornamental Design for Linoleum, Oil-Cloth, or Floor-Covering, of which the following is a full, clear, and exact description, reference being had to the accompanying drawing, forming part of this specification.

The figure is a plan view of a piece of linoleum embodying my design.

I claim:

The ornamental design for linoleum, oil cloth, or floor covering as shown.

In testimony whereof, I have hereunto set my hand.

HARRY HUMPHREYS.
